LIQUID DETERGENT FEEDING DEVICE

Herbert J. Atkinson, Sudbury, Mass.

Application February 10, 1950, Serial No. 143,542

1. A method of making a film, comprising:

1 Claim. (Cl. 222—453)

This invention relates to cleaning devices such as dish mops, floor mops and toilet cleaners in which a mass of cleaning, scrubbing or wiping material is secured to one end of a rigid stick or handle. Such devices are commonly used with water containing a soap or some detergent agent in solution.

It is the general object of my invention to provide a cleaning device which includes a self-contained means for supplying a portion of such a cleansing agent in liquid form while the device is in use. I also provide improved means for dispensing such a liquid cleansing agent, preferably by simple pressure of the stick or handle against some fixed surface, such as the bottom of a pan or pail.

My invention further relates to arrangements and combinations of parts which will be herein-after described and more particularly pointed out in the appended claims.

A preferred form of the invention as embodied in a dish mop is shown in the drawings, in which:

Fig. 1 is a sectional side elevation of a dish mop, partially broken away to show interior structure;

Fig. 2 is an enlarged partial side elevation of the dispensing end of the dish mop; and

Figs. 3 and 4 are detail views, looking in the directions of the arrows 3 and 4 in Fig. 2.

A collar 12 may be cemented or otherwise secured to the outside of the tube 10 near one end thereof, and a mop M may be secured to the end of the tube 10 in any convenient manner, as by looping the component threads T about a ring 14 disposed at one side of the collar 12, and by confining the threads T by a ring 16 at the opposite side of the collar 12.

The details of construction of the mop and its attachment form no part of my present invention.

A valve **V** is mounted in the right-hand end of the tube **10** (as viewed in Fig. 1) and is shown in enlarged detail in Fig. 2. A double-beveled sleeve **20** is secured in the end of the tube **10** and projects outward therefrom. A valve member **22** is slidably mounted in the tube **10** and has a conical face **23** adapted to seat against the beveled inner end **24** of the sleeve **20**.

The inner end portion 26 of the valve V is freely slideable in the tube 10 and acts as a guide for the inner end of the valve. The end portion

26 is preferably provided with a plurality of notches 28 (Fig. 4) to permit the cleansing liquid to pass freely by the valve member 22 when the valve is open.

5. The valve member 22 has a stem 30 extending outward through the sleeve 20 and provided with a head 32. The stem 30 has a plurality of radiating vanes 34 fixed thereto and freely slideable in the sleeve 20. These vanes provide additional 10 guiding surfaces.

The sleeve 20 has a shoulder 36 to receive one end of a spring 40 which encircles the plunger 30 and has its outer end seated in a recess 42 in the inner side of the head 32. The inner face 15 44 of the head 32 is preferably beveled to correspond to the bevel of the adjacent end 45 of the sleeve 20.

The outer end of the sleeve 20 is preferably notched as indicated at 50 (Fig. 3) to provide a clear path for the liquid when the valve is opened and when the head 32 is pressed against the end 45 of the sleeve 20. A plug 55 is removably mounted in the left-hand end of the tube 10.

When the device is to be used, the plug 55 is removed and the tube 10 is filled to any desired extent with liquid soap or with any other liquid detergent or cleansing material. The plug 55 is then reinserted and the liquid material will be stored in the tube 10 until desired for use.

30   If the mop is then pressed against a fixed surface, such as the bottom of a pan or pail, the valve V will be pushed inward and will be thus opened, and a portion of the liquid cleansing agent will flow through the valve and into the water in the pan or other container which is in use in the cleaning operation. As soon as pressure is removed, the valve is automatically closed and prevents further escape of the liquid agent.

35

40 A small hole 70 may be provided in the plug
55 to vent the tube 10.

40 As the valve V is pushed inward, the valve surfaces 26 and the vanes 34 guide and center the valve and prevent binding thereof, and the beveled surface 44 of the head 32 also acts to center the valve as it is seated against the beveled surface 45 of the sleeve 20. This latter action is particularly desirable where the pressure on the head 32 is in part transverse instead of axial.

50 A cleaning device constructed as above described has been found very convenient and useful and makes it possible to supply any desired proportion of soap or other cleansing agent without interrupting the dish washing, mopping or
55 other cleaning process.

Having thus described my invention and the advantages thereof, I do not wish to be limited to the details herein disclosed, otherwise than as set forth in the claim, but what I claim is:

A dispensing device for a liquid comprising an elongated hollow cylindrical container for said liquid, a sleeve secured in and projecting partially from one end of said container and having oppositely-beveled inner and outer end surfaces and having an outwardly-facing internal shoulder, a valve member slidable in said container and sleeve and having inner and outer enlarged ends, a reduced connecting portion and a plurality of guiding vanes thereon, the inner end of said valve member having a short cylindrical portion loosely slideable in said container, said cylindrical portion having a plurality of longitudinal grooves about its periphery to allow flow of liquid past the inner end of said valve member when the valve is open, and said valve member having a frusto-conical portion seated against the beveled inner end of said sleeve when the valve is closed, the outer end of said valve member being normally spaced from the outer end surface of said sleeve and said outer end having a frusto-conical inner surface to seat

against the outer beveled end of said sleeve when the valve is open, and said sleeve having a plurality of end notches extending above the beveled outer end surface of said sleeve and providing radial passages for liquid when the valve is fully open and when the frusto-conical inner surface of the outer end of the valve member is seated against the beveled end surface of the sleeve, and a spring compressed between the internal shoulder in the sleeve and the inner face of the outer enlarged end of said valve member and effective to normally close said valve.

HERBERT J. ATKINSON.
